WIDE-RANGE SATURABLE-REACTOR TUBE-FIRING CIRCUIT

Louis A. Casanova, Pittsburgh, Pa., assignor to Westinghouse Electric Corporation, East Pittsburgh, Pa., a corporation of Pennsylvania

Application October 15, 1953, Serial No. 386,320

5 Claims. (Cl. 321—40)

My invention relates to excitation-means for ignitron rectifiers or inverters, or for other controlled tubes, and the special feature of my invention is the provision of means for obtaining a sufficiently wide range of phase-delays of rectifier-tubes, or a sufficiently wide range of phase-advances of inverter-tubes, to be able to quickly change from no-load to full-load, or from no-voltage output to full-voltage output, by phase-control. More particularly, my invention relates to an all-electronic or all-static control-means of the indicated range, specifically providing a phase-angle control-range of at least 100°, and preferably at least 115°. To provide a reasonable factor of safety, I aim at a phase-adjustment of a maximum of 120°, for most power-interchanging conversion-apparatus using my invention for interchanging controllable power between two diverse electric systems. It is conceivable, however, that a need may arise for such a system in which the phase-angle control extends over a range of 180°, or even more, and I contemplate such a system within the scope of my invention.

More particularly, my invention relates to ignitrons or other controlled tubes in which firing-capacitors are used, to discharge through saturable series reactors into an ignitor or other make-alive anode or control-circuit. The firing-angles of such tubes may be varied over a phase-angle range of about 60°, by means of a controllably saturable phase-shifting reactor which is connected between the source of excitation-voltage and the firing-capacitor, without making it impossible to initiate the firing-operation of the tubes even when the excitation-voltage falls to approximately one-half of its normal value, meanwhile maintaining stability and an approximately constant voltage-regulation over the entire phase-shift range.

In most rectifier or inverter systems, a phase-shift range of 60° is not enough to effect a complete load-control from no-load to full-load, as it is usually necessary to provide a phase-shift of anywhere from 100° to 115° in order to effect a complete load-change in tube-circuits of different descriptions. It is conceivable that there may be some circuits which require a phase-shift control approaching 180° or even more.

In order to obtain a rapid phase-shift control, while at the same time facilitating adaptation of the control-device to automatic regulation, it is desirable that as much as possible of this phase-shift control, namely 60°, shall be provided for by the above-mentioned controllably saturable phase-shifting reactors. When a wider angle of phase-shift control is needed, this has been provided heretofore by means of mechanically movable phase-shifters, which involve a significant amount of rotor-inertia, and consequently involve a slight time-delay in rotating the rotor-members of these phase-shifters.

An important field of application of my invention is in rectifier-devices which replace motor-generator sets. If a rectifier-device is to be able to successfully replace a motor-generator set, it is obvious that the performance of the rectifier-control must equal that of the motor-generator set. Since the speed of response of the voltage-

2

control of a motor-generator set is very high, involving only a change in the field-excitation strength of the generator, it is necessary also for the rectifier-control to be capable of very quickly changing the firing angle from a zero delay to a delay of anywhere from 100° to 120°, more or less, as may be necessary in any particular rectifier-circuit. My invention is particularly needed in such a situation, and in other applications wherein a rapid phase-angle change is needed, over a wide angular range.

I achieve the objects of my invention by omitting the above-mentioned mechanically rotating phase-shifter, and replacing the same with one or more phase-shifting networks which are serially connected between the excitation-voltage source and a firing-circuit which is provided with the usual controllably saturable phase-shifting reactor. This phase-shifting network, or each one of said networks, if there are more than one, includes a parallel-capacitor and a parallel-connected saturable reactor, these two devices having an unsaturated circulating current which is at least four times larger, and preferably from five to seven or eight times larger (or even more), than the load-currents which are drawn therefrom by the firing-circuit, if there is only one such phase-shifting network, or the load-currents which are drawn by the next phase-shifting network, if there are two or more serially connected phase-shifting networks. Each phase-shifting network is provided with a charging-circuit which serially includes its own controllably saturable phase-shifting reactor. Means are provided for controlling the saturations of all of the phase-shifting reactors, preferably by means of a single variable resistance, which can be either manually or automatically controlled, and this may be accomplished at a very high speed, from one extreme of the adjustment-range to the other.

An exemplary form of embodiment of my invention is shown in the accompanying drawing, the single figure of which represents a simplified circuit-diagram of circuits and apparatus illustrative of the principles of application of my invention.

I have shown my invention as a conversion-apparatus for interchanging controllable power between an alternating-current system, such as a three-phase system AC, and a direct-current system DC having terminals (+) and (—). While I have illustrated the AC system as being a three-phase system, it could also be a single-phase system, or a polyphase system of a different number of phases. Furthermore, while I have shown the second electric system as a DC system, it is to be understood that this second system could be either a direct-current system or an alternating-current system having a different frequency than the system marked AC. In general, it is desirable that at least one of these systems should be an alternating-current system having a self-sustained frequency and having a normal voltage which is subject, at times, to voltage-fluctuations, and it is to be understood that the system marked AC is a power-line having such characteristics. The power may be interchanged in either direction, between these two systems, depending upon the tube-control.

My conversion-apparatus is shown as a double three-phase rectifier-system, using a main transformer MT, having a delta primary which is energized from the AC system, and having two star-connected secondary windings which provide the consecutive secondary phases numbered 1 to 6. The star-points of the two secondary windings are connected by an interphase transformer IT, the mid-point of which is connected to the negative direct-current load-terminal (—). The six secondary phases 1 to 6 are used to energize the anodes of six ignitron-tubes, of which only two tubes are shown, namely the tubes T1 and T4 which are connected to the dia-

metric opposite secondary phases 1 and 4, respectively. The other tubes will be connected to the other secondary phases, as will be well understood. Each tube has a main anode A, a mercury or other vaporizable cathode C, and an ignitor or other make-alive anode I, with suitable numerical suffixes corresponding to the secondary phase-number. The cathodes are all connected together in a common circuit which is the positive terminal (+) of the DC load-circuit.

It is usually convenient and economical to provide an auxiliary transformer XT, which energizes an auxiliary alternating-current bus XAC from the main alternating-current power-line AC, transforming the power-line voltage from whatever value it may have, for example 6900 volts, to some convenient standard auxiliary voltage, such as 230 volts. Various equipments are energized from the auxiliary bus XAC. So far as my present invention is concerned, I have shown an excitation-transformer ET as having a delta primary winding which is energized from this auxiliary bus XAC, and as having a dog-leg or zig-zag connected secondary winding providing secondary phases numbered from 1' to 6', so as to provide excitation-voltages which are suitably phased with respect to the correspondingly numbered anode-circuit voltages, so as to give the proper firing-voltages for the ignitron-tubes T1 to T6, taking into consideration the particular firing or controlling-circuits which are being used in any particular case.

Each diametrically connected pair of tubes, such as T1 and T4, is provided with a firing-capacitor Cf, which discharges through a serially connected, constantly saturable series reactor Xs, which is connected between one terminal 11 of the firing-capacitor Cf and a circuit 12 which is in turn serially connected, through a positive-wave contact-rectifier or other asymmetrically conducting device Rs1, to the ignitor I1 of the first tube T1. The other terminal of the firing-capacitor Cf is indicated at 13, and this terminal is serially connected through a positive-wave rectifier Rs4 to the ignitor I4 of the diametrically connected tube T4. A shunt-connected circuit-device must be provided for completing the circuits for the two opposite-polarity currents which are drawn by the ignitors I1 and I4. In the illustrated system, this is done by means of shunt or parallel-connected negative-wave rectifiers Rp1 and Rp4, which are connected between the cathode-bus (+), and the circuits 12 and 13, respectively. The usual firing-circuit contains not only the firing-capacitor Cf and the saturable series reactor Xs, but also a controllably saturable phase-shifting reactor Xps1, which is serially connected between the terminal 11 of the firing-capacitor Cf and a charging-circuit 14 for this capacitor. The degree of saturation of the phase-shifting reactor Xps1 is controlled by means of a direct-current saturating-coil 15.

As has been previously pointed out, and as has been known in the art, the firing-circuit which is contained between the conductors 14-13 and the respective ignitors I1 and I4 is known, and it is known to be stable, and to maintain a fairly constant firing-voltage on the ignitors, throughout phase-angle changes of as much as 60°, in a 60-cycle system. It is known that the related magnitudes of the capacitive reactance of the firing-capacitor Cf and the unsaturated inductive reactance of the series reactor Xs may easily be chosen, largely by empirical methods, so that the firing-operation of the tubes T1 and T4 will commence, even through the AC line-voltage should drop to 50% of its normal value. This condition is usually imposed, so that the rectifier will be able to start under low line-voltage conditions, with a generous margin of safety, under all operating-conditions.

In accordance with my present invention, I provide one or more phase-shifting networks, which are serially connected between the excitation-transformer secondary-phase 1'-4' and the firing-circuit input-terminals 14-13, respectively. Each of these phase-shifting networks is

capable of providing an extra 60° of phase-shift adjustment, in addition to the 60° which is provided by the firing-circuit. In most rectifying systems, including the system which is illustrated, only one of these phase-shifting networks is needed, so as to give a total phase-angle adjustment of 120°, including the 60° of adjustment which is provided by the firing-circuit. It is to be understood, however, that if a wider phase-angle adjustment is needed, it is possible to serially add as many phase-shifting networks as may be needed, in order to secure the total overall range.

The illustrated phase-shifting network comprises a parallel capacitor Cf and a parallel-connected, constantly saturable reactor Xp, both of which are connected across the terminals 14 and 13, respectively. The parallel-connected capacitor Cf and reactor Xp have an unsaturated circulating current which is several times, and preferably from five to eight times, the load-current which is drawn by the firing-circuit, more or less. Probably never less than one-fourth of said circulating current would be withdrawn from the parallel-connected capacitor Cf and reactor Xp, to charge the firing-capacitor Cf. The phase-shifting network also includes a second controllably saturable phase-shifting reactor Xps2, which is serially connected between the circuit 14 and the secondary terminal 1' of the excitation-transformer ET. The saturation of this phase-shifting reactor Xps2 is controlled by means of a direct-current saturating-coil 16. The circuit 13 is connected to the secondary terminal 4' of the excitation-transformer ET.

The above-described apparatus makes it convenient to provide a single control, for controlling the two saturating-coils 15 and 16, or for simultaneously controlling all of such coils, in case there should be more than two, that is, in cases using more than one phase-shifting network in addition to the firing-circuit. Conveniently, these two saturating-coils 15 and 16 are connected in series, and are energized with controllable direct-current by any suitable means, such as a battery-circuit represented by the terminals B+ and B-, and a serially connected rheostat or variable resistance 17, which can be controlled either manually or by means of an automatic regulator (not shown). It is possible, by suitable switching-means, which is the ordinary means for varying a resistance such as 17, to vary the magnitude of the direct-current saturating-current from its full value to zero, or vice versa, with practically no time-lag, and hence it is possible to change the ignition phase-angle of the controlled rectifier-tubes T1 and T4 with speeds of response which rival or exceed the speeds which are obtainable with motor-generator sets.

The operation of the pulsed-current ignitor-circuits, with non-linear inductances connected therewith, such as the inductances Xs, Xps1, Xp, and Xps2, and with their non-sinusoidally charged and discharged capacitors, such as Cf and Cp, defies strict mathematical analysis, and even analysis by means of the calculating board. The performance of such circuits is largely unpredictable, and must be empirically determined, and the design-constants must be largely determined, or at least checked, by test. It has been found that the illustrated circuit operates in the manner which has been described.

It will be understood that the ignitor-tubes T1 and T4 could have been replaced by other types of tubes, each tube having a main anode-and-cathode circuit and a control-circuit. It will also be understood that these tubes, by a proper phasing of the excitation-voltages therefor, could be used either for rectifier-operation or inverter-operation.

It will also be understood that the control-element of the tube T1 does not need to be an ignitor I1 or other make-alive element; but if it is an ignitor, it should be protected against the negative portions of the control-voltage, as by the contact-rectifiers such as Rs1, Rs4, Rp1 and Rp4, as is well known in the art.

It will be noted that the so-called firing-capacitor Cf

is a parallel-connected capacitor, which is connected in parallel-circuit relation across the terminals of the impressed single-phase control-source. It will further be noted that the so-called series reactor X_s is actually connected in a parallel circuit, $X_s-R_{s1}-I1-C1-R_{p4}$, across the terminals 12, 13 of the parallel-connected capacitor C_F , and that nearly all of the voltage-drop in this parallel circuit occurs in the substantially constantly saturable reactor X_s . It will be understood that the control-circuit $I1-C1$ of the tube $T1$ could be supplied or energized in any way from the output-side of the phase-shifting network which is made up by a controllably saturable reactor X_{ps1} , in the energizing-circuit for a parallel-connected capacitor C_F and constantly saturable reactor X_s . I thus use two (or more) similar, serially connected, phase-shifting networks, $X_{ps2}-C_F-X_p$, and $X_{ps1}-C_F-X_s$. In each network, the controllably saturable reactor controls the phase-lag which must occur, in each half-cycle, before the capacitor reaches the instantaneous voltage-value necessary to saturate the constantly saturable reactor, and that the constantly saturable reactor thereafter holds or "regulates" the capacitor-voltage at approximately this value, until near the end of that half-cycle.

It is contemplated that the previously mentioned changes and equivalencies are within the scope of my invention, in its broader aspects.

I claim as my invention:

1. A conversion apparatus for interchanging electric energy between two different electric systems, at least one of said systems being an alternating current system, said apparatus comprising at least one tube having a main anode-cathode circuit and a control circuit, main circuit connections for connecting the main anode-cathode circuit of each tube between the systems for energy interchange therebetween, excitation means for providing an alternating current excitation voltage having a predetermined phase relation to the voltage of said alternating current system, a plurality of serially connected phase shifting networks, serially connected between said excitation means and the control circuit of each tube, each phase shifting network including a capacitor and a substantially constantly saturable reactor connected in parallel across the capacitor, each phase shifting network also having a charging circuit which serially includes a controllably saturable phase shifting reactor for charging its capacitor, and means for controlling the saturations of all of the phase shifting reactors.

2. A conversion apparatus for interchanging electric energy between two different electric systems, at least one of said systems being an alternating current system, said apparatus comprising at least one tube having a main anode-cathode circuit and a control circuit, main circuit connections for connecting the main anode-cathode circuit of each tube between the systems for energy interchange therebetween, excitation means for obtaining an alternating current excitation voltage from said alternating current system, a plurality of serially connected phase shifting networks, serially connected between said excitation means and the control circuit of each tube, each phase shifting network including a capacitor and a substantially constantly saturable reactor connected in parallel across the capacitor, each phase shifting network also having a charging circuit which serially includes a controllably saturable phase shifting reactor for charging its capacitor, and means for controlling the saturations of all of the phase shifting reactors.

3. A conversion apparatus for interchanging electric energy between two different electric systems, at least one of said systems being an alternating current system, said apparatus comprising at least one tube having a main anode-cathode circuit and a control circuit, main circuit connections for connecting the main anode-cathode circuit of each tube between the systems for energy interchange therebetween, control circuit means including a

capacitor and a saturable series reactor connected between said capacitor and the control circuit of each of said tubes in a circuit extending in parallel across said capacitor, said control circuit means also including a charging circuit which serially includes a controllably saturable phase shifting reactor for charging said capacitor, excitation means for obtaining an alternating current excitation voltage from said alternating current system, at least one phase shifting network serially connected between said excitation means and said control circuit means, each phase shifting network having a charging circuit which serially includes a controllably saturable phase shifting reactor for charging its parallel-connected capacitor, and means for controlling the saturations of all of the phase shifting reactors.

4. A conversion apparatus for interchanging electric energy between two different electric systems, at least one of said systems being an alternating current system, said apparatus comprising at least one tube having a main anode-cathode circuit and a control circuit, main circuit connections for connecting the main anode-cathode circuit of each tube between the systems for energy interchange therebetween, control circuit means including a capacitor and a saturable series reactor connected between said capacitor and the control circuit of each of said tubes in a circuit extending in parallel across said capacitor, said control circuit means also including a charging circuit which serially includes a controllably saturable phase shifting reactor for charging said capacitor, excitation means for obtaining an alternating current excitation voltage from said alternating current system, at least one phase shifting network serially connected between said excitation means and said control circuit means, each phase shifting network including a parallel-connected capacitor and a substantially constantly saturable reactor connected in a circuit extending in parallel across the associated capacitor, each phase shifting network having a charging circuit which serially includes a controllably saturable phase shifting reactor for charging its parallel-connected capacitor, the substantially constantly saturable reactor of each phase shifting network having an unsaturated circulating current which is at least several times larger than the load currents which are drawn therefrom by the circuit which is energized thereby.

5. A conversion apparatus for interchanging electric energy between two different electric systems, at least one of said systems being an alternating current system, said apparatus comprising at least one tube having a main anode-cathode circuit and a control circuit, main circuit connections for connecting the main anode-cathode circuit of each tube between the systems for energy interchange therebetween, control circuit means including a capacitor and a saturable series reactor connected between said capacitor and the control circuit of each of said tubes in a circuit extending in parallel across said capacitor, said control circuit means also including a charging circuit which serially includes a controllably saturable phase shifting reactor for charging said capacitor, excitation means for obtaining an alternating current excitation voltage from said alternating current system, at least one phase shifting network serially connected between said excitation means and said control circuit means, each phase shifting network including a parallel-connected capacitor and a substantially constantly saturable reactor connected in a circuit extending in parallel across the associated capacitor, each phase shifting network having a charging circuit which serially includes a controllably saturable phase shifting reactor for charging its parallel-connected capacitor, the parallel-connected capacitor and substantially constantly saturable reactor of each phase shifting network having such related magnitudes that the operation of the controlled tube can be initiated, and stability

and an approximately constant voltage regulation maintained on each of the parallel-connected capacitors, even though the excitation voltage of the excitation means falls to approximately one-half of its normal value.
